GARMENT PRESSING MACHINE

Thomas Yosyk, Ridgewood, N. Y.

Application July 17, 1934, Serial No. 735,659

4 Claims. (Cl. 68—9)

My present invention relates to garment pressing machines and has particular reference to means for facilitating the drying of the garments or fabrics which have been pressed thereon.

In the usual type of garment pressing machines comprising a pair of relatively movable pressing elements, such as the usual head and buck, there has been provided suction apparatus for drawing air through the garments after they have been steamed and pressed. However, the garment pressing machines made prior to my invention and which were equipped with suction apparatus for drawing air through the garments, require that the head be raised before the air can be drawn through the garment to remove excess moisture therefrom. A serious objection to drawing the air through the garments after the head has been raised is that the air is drawn down at room or atmospheric temperatures against and through the hot and moist garment, so that the steam or hot vapor in the garment when contacted by the cool air condenses and the garment is not as effectively dried as is possible with apparatus embodying my invention, which provides for drawing preheated air through the garment while the pressing elements are still in pressing relation, and, therefore, without exposing the garment to atmospheric or room temperatures.

Means by which I accomplish the foregoing are illustrated in the accompanying drawings, it being understood that the drawings disclose preferred illustrative embodiments of the invention, and that variations in the construction and arrangement of the parts for accomplishing the above specified purpose may be made, as herein-after pointed out.

In the drawings,

Fig. 1 is a longitudinal central sectional view through the head of a pressing machine showing a front elevation of portions of the buck and the steaming valve;

Fig. 2 is a view similar to Fig. 1 showing a portion of the buck broken away and showing a conventional suction apparatus applied to the buck;

Fig. 3 is an enlarged fragmentary sectional view of a fragment of the head and buck showing a modification in mechanism embodying my invention applied to the head;

Fig. 4 is a fragmentary sectional view of the pressing head with another modification of my invention applied thereto; and

Fig. 5 is a view similar to Fig. 3 showing a further modification.

In the drawings, the letter H designates generally the pressing head which has a chamber 5

formed between the top plate 6 and intermediate plate 7, into which steam is admitted through an inlet 8 from any suitable source of supply. A valve body 9 is screw threaded into the intermediate plate 7 and extends through the top plate 6 against which it is tightly sealed by any suitable means. A passage 10 in the valve communicates with the chamber 5, and another passage 11 communicates with the spray chamber 12 which is formed between the plate 7 and the perforated plate 13 forming the lower face of the head. The valve 14 is provided with a seat 14a at the top of the passage 10 for the disc 14 carried by a stem 15 which is connected to lever 16 pivoted on uprights 17 on top of the valve. Communication between the passages 10 and 11 may be established to permit steam to flow from the chamber 5 to the chamber 12 and through the perforations of the plate 13 in usual manner when pressing by operating lever 16 to raise disc 14.

The buck is designated generally by the letter B and it includes a top perforated plate 18 and a baffle plate 19 providing a chamber 20 into which the steam is projected when the valve head 14 is raised from the seat 13 in known and usual manner. I have also shown in Fig. 2 a known type of suction apparatus, such as shown in Patent 1,193,093, including a pipe 21 which communicates with chamber 20 and also with a fan 22 which has an outlet 23. In the pipe 21 between the fan 22 and the buck is a valve 24 controlled by rod 25 connected to a bell crank 26 which is pivoted on a bracket 27 supported by the buck. Another rod 28 is connected to a foot pedal 29 and to the bell crank. 30 35

The apparatus thus far described is not original with me and is shown purely for the purpose of illustration, since my invention about to be described may be used in connection with various types of heads and exhausting or suction apparatus. It is with apparatus of the type shown and described and similar machines that the garments or fabrics F between the head and buck are steamed and pressed when the head is clamped down against the buck either by the usual treadle operated levers or power mechanism not shown, and after which the head must be raised from the fabric before the suction apparatus can function. Obviously, when the pedal 29 is depressed the bell crank 26 will be 40 45 50 55 rocked and the valve 24 opened, so that air may be sucked through the fabric or garment and buck through the perforations in the plate 18 and chamber 20. With the head elevated, this air is at atmospheric or room temperature

and results in the condensation above mentioned.

To more effectively and quickly dry the garments, I provide for drawing the air through the head while it is in pressing relation with the buck and fabrics or garments therebetween, and while so doing heating the air to avoid the condensation which results from drawing air at atmospheric or room temperatures through garments or fabrics with the head raised.

In Figs. 1 and 2, I have shown a tubular passage 30 at each side of the valve 9 formed through the head between the plates 6 and 7 and communicating at their lower ends with the chambers 12. On top of the plate 6 above the passages 30 there are bosses 31 screw threaded on their interiors to receive the lower screw threaded ends 32 of valves designated generally by the numeral 33. These valves have on their interior ribs or webs 34 provided with lugs 35 on their lower ends. A disc 36 is loosely mounted in the valve and normally rests on the lugs 35 spaced from the shoulder 37 on the interior of the valve beneath the port 38. Since the walls of the passages 30 extend through the steam receiving chamber 5, they are heated so long as the chamber 5 is supplied with steam, that is, when the apparatus is in use.

I wish it to be understood that while I have shown two of the valves 33 located at corresponding points on the head, that I may provide only one of such valves or more than two and locate them at any point or points on the head which I may select.

In Fig. 1, the steam valve is shown open and the arrows indicate the passage of the steam into the chamber 5 from the inlet 8 through the passage 10 and down through passage 11 into chamber 12, and thence through the openings in the perforated plate 13 to steam the garment or fabric while it is being pressed. In this open position of the steam valve, the air valves 33 are automatically closed by the steam pressure as indicated by the arrows showing the steam entering the passages 30 and consequently lifting the discs 36 into engagement with the shoulders 37 and closing the ports 38. However, as shown in Fig. 2, when the steam valve is closed the pressure on the discs 36 is released and they 50 gravitate down onto the lugs 35 in the port 38, so that air may flow through the ports around the discs in the spaces between the ribs 34 and down through the passages 30 into the chamber 12. This flow of the air is facilitated by operation of the suction apparatus, for obviously, when the valve 24 is opened in the manner previously described, the air is sucked through the passages 30 and chambers 12 and 20 in considerable volume, while at the same time being heated by 55 contact with the heated walls of the passages 30 and the heated plates 7 and 13 of the head.

In actual practice, I find that garments and fabrics when subjected to the drying action provided by my invention, are far more completely and quickly dried than when air at atmospheric or room temperatures is passed through them with the head raised.

To facilitate or increase the heating of the air which is drawn through the garments in the manner above explained, I may provide, as shown in Fig. 3, in connection with the apparatus such as shown and described in Figs. 1 and 2, a baffle plate 40 immediately beneath each of the passages 30 or either one of them and spaced from the heated plate 7. The distance which the baffle

plates 40 are spaced from the plate 7 may be determined by spacer blocks 31 through which and the plates 40 extend screws 42 which engage into the plate 7 to hold the baffle plates 40 in place. The plates 40, as well as the plate 7, will be heated, and due to the restricted area therebetween, the air will be additionally heated as it enters the chamber.

While I have shown in Figs. 1-3 a gravity actuated valve vertically mounted on top of the head, it is possible to provide a horizontal hinged valve to admit air through the side of the head, as shown in Fig. 4, wherein a valve casing 43 is screw threaded into the side wall 44 of the head in alinement with a passage 45 which communicates with the chamber 12' corresponding to the chamber 12. The valve casing 43 is provided with an internal shoulder 46 against which the valve 47 is forced to close the passage 45 or its communication with the atmosphere when the steam is being sprayed as previously described, the valve 47 being pivotally mounted at 48 in the top of the valve casing. When the suction is applied, the valve 47 swings to open position on its pivot 48 admitting the air. Also if desired, a baffle plate similar to the baffle plate 40 in Fig. 3, may be mounted beneath the passage 45 to increase the heating of the air as it enters. There may be as many valves 43 as desired on each head.

In Fig. 5, I have shown an arrangement generally similar to the air valves of Figs. 1-3, except that a plate 50 closes the top of the valve and provides a space 51 above the top of the head through which air is drawn and preheated. The air then passes through openings 52 and between the ribs which support the disc as in the other embodiments of the invention.

I do not wish to limit the invention to the specific construction and arrangement of valves 40 shown and described nor the exact manner in which they are connected to the head, and of course the invention may be practiced in connection with various types of pressing machines whether manually or power operated. I also 45 wish to point out that it is not absolutely necessary to the practice of the invention to have the steam spraying valve on the head alone as there may be a steam spraying valve on both the head and buck either of which may be used.

I claim:

1. In a pressing machine having cooperating upper and lower pressing elements, a steam spraying chamber in the upper element, a passage in said upper element communicating with the atmosphere at one end and with the spraying chamber at its other end, a valve in said passage, means to pass steam through said chamber, lower element and garments therebetween, and suction means to draw air through said passage, spraying chamber, lower element and garments therebetween, said valve being movable by the passage of steam through said heating chamber to closed position and movable by the action of the suction means to open position.

2. In a pressing machine having cooperating upper and lower pressing elements, a steam spraying chamber in the upper element, a passage in said upper element communicating with the atmosphere at one end and with the spraying chamber at its other end, a valve in said passage, means to pass steam through said chamber, lower element and garments therebetween, and suction means to draw air through said passage, spraying chamber, lower element and garments there-

between, said valve being movable by the passage of steam through said spraying chamber to closed position and movable by the action of the suction means to open position, and a heated surface provided on said upper element adjacent at least one end of said passage to be contacted by the air as it is drawn in to heat the air prior to its passage through the garments.

3. In a pressing machine having cooperating upper and lower pressing elements, a heated chamber in the upper element, means on the upper element to pass steam through garments or fabrics between the elements with the elements in pressing relation, at least one conduit extending through said heated chamber to be directly heated by the heating medium therein, suction means to draw air through said conduit, pressing elements, and garments or fabrics therebetween, and a valve associated with said conduit operable by the pressure of the steam passing through said elements and garments or fabrics therebetween to close the conduit, and said valve being operable by the action of the suction means to open the conduit to permit air to be drawn down through said conduit to be heated therein and pass through

the garments or fabrics with the elements in pressing relation.

4. In a pressing machine having cooperating upper and lower pressing elements, a heated chamber in the upper element, means on the upper element to pass steam through garments or fabrics between the elements with the elements in pressing relation, at least one conduit extending through said heated chamber to be directly heated by the heating medium therein, suction means to draw air through said conduit, pressing elements, and garments or fabrics therebetween, and a valve associated with said conduit operable by the pressure of the steam passing through said elements and garments or fabrics therebetween to close the conduit, and said valve being operable by the action of the suction means to open the conduit to permit air to be drawn down through said conduit to be heated therein and pass through the garments or fabrics with the elements in pressing relation, and a plate independent of the walls of the heating chamber slightly spaced therefrom and providing in connection therewith a space through which the air must travel to be additionally heated.
